UNITED STATES PATENT OFFICE.

CULLEN L. HUNTOON, OF LOS ANGELES, CALIFORNIA.

DESIGN FOR AN AUTOMOBILE LIGHT-REFLECTING STAR.

Application filed December 8, 1925. Serial No. 15,686. Term of patent 3½ years.

To all whom it may concern:

Be it known that I, CULLEN L. HUNTOON, a citizen of the United States, residing at Los Angeles, in the county of Los Angeles and State of California, have invented a new, original, and ornamental Design for an Automobile Light-Reflecting Star, of which the following is a specification, reference being had to the accompanying drawing, forming part thereof.

In the drawing Fig. 1 is a perspective view taken from the front and Fig. 2 is a perspective view taken from the back of the automobile light reflecting star.

I claim:

The ornamental design for an automobile light reflecting star, as shown.

CULLEN L. HUNTOON.
